Primary Examiner — Jack Reickel*Assistant Examiner* — Bobby W Jones, II(74) *Attorney, Agent, or Firm* — Bradley J. Thorson; DeWitt LLP(57) **CLAIM**

The ornamental design for a heat pipe, as shown and described.

DESCRIPTION

FIG. 1 is a perspective view of a heat pipe showing my design;

FIG. 2 is a front view thereof;

FIG. 3 is a rear view thereof;

FIG. 4 is a left view thereof;

FIG. 5 is a right view thereof;

FIG. 6 is a top plan view thereof; and,

FIG. 7 is a bottom plan view thereof.

1 Claim, 7 Drawing Sheets(56)
